(57) **CLAIM**

The ornamental design for a vehicle mirror, as shown and described.

DESCRIPTION

FIG. 1 is a front elevational view of a left vehicle mirror, showing the base in solid line and the mirror and arm in broken line;

FIG. 2 is a top plan view of the base of the left vehicle mirror; FIG. 3 is a bottom plan view of the base of the left vehicle mirror;

FIG. 4 is a back elevational view of the base of the left vehicle mirror;

FIG. 5 is a left side elevational view of the base of the left vehicle mirror;

FIG. 6 is a right side elevational view of the base of the left vehicle mirror;

FIG. 7 is a perspective of the base of the left vehicle mirror;

FIG. 8 is a front elevational view of a right vehicle mirror, showing the base in solid line and the mirror and arm in broken line;

FIG. 9 is a top plan view of the base of the right vehicle mirror; FIG. 10 is a bottom plan view of the base of the right vehicle mirror;

FIG. 11 is a back elevational view of the base of the right vehicle mirror;

FIG. 12 is a left side elevational view of the base of the right vehicle mirror;

FIG. 13 is a right side elevational view of the base of the right vehicle mirror; and,

FIG. 14 is a perspective of the base of the right vehicle mirror. In the drawings, the broken lines depict portions of the article that form no part of the claimed design.
